UNITED STATES PATENT OFFICE.

ARNOLD STUCKI, OF ALLEGHENY, PENNSYLVANIA, ASSIGNOR TO STAND-ARD STEEL CAR CO., OF PITTSBURG, PENNSYLVANIA, A CORPORATION OF PENNSYLVANIA.

METALLIC CAR.

SPECIFICATION forming part of Letters Patent No. 752,311, dated February 16, 1904.

Application filed September 10, 1903. Serial No. 172,597. (No model.)

To all whom it may concern:

Be it known that I, ARNOLD STUCKI, a resident of Allegheny, in the county of Allegheny and State of Pennsylvania, have invented a new and useful Improvement in Metallic Cars; and I do hereby declare the following to be a full, clear, and exact description thereof.

My invention relates to railway-cars, and more especially to metallic gondola and hopper cars.

The object of my invention is to so construct such cars that the upper edges of the metallic sides are prevented from bulging or swinging outwardly, so that the car sides will always be held in a substantially vertical plane and their full carrying capacity thus made effective.

In all prior gondola and hopper car constructions wherein the sides of the car are formed as plate-girders to carry a portion or all of the load the car sides have been connected to the floor-plates and transverse floor-supports in such a manner that the fastenings would not withstand the force of the load pressing from the inside of the car, this pressure having a strong tendency to push or bulge the top edges of the sides outwardly, the construction being such that the stakes had a very insecure fastening at their lower ends to the floor and floor-supports, so that the top angles of the car sides were allowed to give or yield. Furthermore, this outward pressure is considerably augmented by the centrifugal force which is present when the car passes curves at high speed. As soon as the top edges of the car sides bulge outwardly the strength of the car side as a carrier of the load is partly overcome. To utilize the full carrying capacity of the car sides, it is necessary to maintain the same in a substantially true vertical plane.

The object of the present invention is to improve gondola and hopper car constructions whereby this defect in prior cars is overcome; and to this end the improvement consists in bending the lower ends of the vertical stakes inwardly and connecting the same securely to the transverse floor-supports, transoms, or bolsters, and in the case of hopper-

cars by also extending the stakes which are opposite the hoppers downwardly entirely or mostly to the bottom of the outside hopper-sheets and securing them thereto, so that the floor-plates will act to stiffen or brace the lower ends of these stakes, thus acting to prevent the upper ends thereof from bulging outwardly and also incidentally stiffening the outside hopper-sheets.

In the accompanying drawings, Figure 1 is a plan view of one half of the car with the floor removed and the sides in section. Fig. 2 is a side view of one half of a twin-hopper gondola car constructed according to my invention. Fig. 3 is a vertical longitudinal section through the other half thereof. Fig. 4 on its left-hand portion is a transverse section on the line 4-4, Fig. 1, and on its right-hand portion on the line 4'-4", Fig. 1; and Fig. 5 on its left-hand portion is a transverse section on the line 5-5, Fig. 1, and on its right-hand portion a similar section on the line 5'-5", Fig. 1.

The car shown is provided with center sills, but no side sills, the car sides being plate-girders and serving not only to confine the lading, but also to carry a considerable portion of the load. The center sill may be of various constructions, being shown as composed of two channel-beams 1, placed with their flanges projecting outwardly, although this is not essential. These center sills extend toward the car ends beyond the body-bolsters 3 and have spliced thereto the draft-beams 4, which extend outwardly and are secured to the ends of the car.

The body-bolster may be of any preferred type, that shown in the drawings being composed of two web filling-pieces 5 on each side of the center sills, cross-braces 6, interposed between the center sills, and a top cover-plate 7, and a bottom cover-plate 8. The braces 6 preferably are pressed shapes formed with flanges on their top, bottom, and side edges, the latter flanges serving as a means to secure the same to the center sills. The web fillers 5 also preferably are pressed members provided with flanges at their top and bottom sides and inner ends, the latter serving as a

means to secure said members to the center sills and the top and bottom flanges serving as convenient means for securing thereto the top and bottom cover-plates. Two such members are placed back to back, as indicated in Fig. 1.

Intermediate the body-bolsters the center sill and car sides are united by transverse floor-supports 10 and at intervals by the deep transoms or cross-bearers 11. The floor-supports 10 may be of any suitable flanged shapes, being shown as angle-bars, and are secured to the center sills by means of angle or knee pieces 12. The cross-bearers 11 are deep trusses comprising top or compression members 13, formed of sections of angle-bar secured to the center sills by means of angle or knee pieces 14 and bottom or tension members 15; also preferably of angle-bars bent into the form shown in Fig. 4 and having their middle portions spaced from the center sills by means of the vertical struts 16, which struts are shown as sections of angle-bar riveted to the webs of the center sills and to a connection-plate 17, secured to the tension member 15 at its middle portion. Preferably two angle-bars 15 will be used, as shown, and the connection-plate 17 will be riveted between the same. The ends of the bars 13 and of the tension members 15 are connected by vertical plates 18. Between the center sills in line with the members 13 are transverse braces or connecting-pieces 19, preferably formed of sections of angle or channel bar, suitably secured to the center sill, as by angle or knee pieces.

The car-body is composed of the floor-plates 20, side plates 21, end plates 22, and suitable strengthening and connecting members. The car sides will be formed as plate-girders. Consequently the side plates are strengthened at their top by the compression-chord 23 and at their bottom by tension-chord 24, which preferably will be angle-bars. The compression-bar 23 is placed with its horizontal flange projecting outwardly, while the lower or tension chord 24 is connected to the side plates with its horizontal flange projecting inwardly, thus serving as a convenient means for securing to said car sides the floor-plates 20, as well as the transverse floor-supports and cross-bearers or transoms.

The vertical stiffening members or stakes of the car are preferably formed from sections of flanged bars and may be either angle-bars, channel-bars, T-bars, bulb-angles, deck-beams, or channel-bars pressed into U shape. These stakes form the vertical stiffeners of the car sides, thus converting the latter into plate-girders, and in order to hold the car sides in a vertical position against the tendency for the same to bulge outwardly the lower ends of said stakes are bent inwardly and secured firmly to the transverse members of the car underframe. Opposite the body-bolsters are

shown channel-shaped stakes 26, having their lower ends 27 bent inwardly and riveted to the flanges on the lower edge of the body-bolster. Opposite the transverse floor-supports 10 the stakes are of lighter construction, preferably being angle-bars 28, and these have their lower ends bent inwardly, as at 29, and riveted firmly to the depending leg or web of the floor-supports 10. Opposite the cross-bearers or transoms the stakes are shown as formed of double-angle construction 30, although a T-bar would answer the same purpose, and these stakes also have their lower ends 31 bent inwardly on an angle, as shown in Fig. 3, and riveted firmly to the cross-bearers, such as to the connection-plate 18. All of these stakes therefore are secured to the transverse members of the frame in such a manner that the upper edges of the car sides cannot bulge outwardly without bending the stakes, the connections shown being such that they will not yield or give. As these stakes have flanges or portions at right angles to the car sides, which flanges or portions are bent and extend inwardly, it is practically impossible to bend said stakes by the outward thrust of ordinary loads. As a consequence the car sides will be held in substantially vertical planes and the full carrying capacity thereof utilized.

In the case of hopper-cars it is the common practice to have the outer hopper-sheets formed as extensions of the car sides, this construction being shown in the drawings, where the outer hopper-sheets 35 are riveted to the depending flange of an angle-bar 36, whose horizontal flange is riveted to the lower flange of the tension angle-bar 24. In prior gondola cars of this type the practice has been to have the stakes 37, which are opposite these hopper-sheets, extend down only to the lower edge of the side plates, and as the floor-plates at the hoppers are inclined downwardly, as shown at 38, the vertical stakes 37 had no support whatsoever other than their connection to the side plates, and consequently offered no resistance to the tendency of the load to bulge the top edge of the side outwardly. In my construction these stakes 37 are extended downwardly practically to the lower edges of the outside hopper-sheets, being bent inwardly, as indicated at 40, Fig. 5, to fit closely against said outer hopper-sheets, and are firmly connected thereto. As a consequence the lower ends of these stakes are braced by means of the transverse floor-plates 38, so that the upper ends of said stakes will not bulge outwardly.

The inside hopper-sheets are shown at 41, the doors at 42, the door-operating mechanism at 43. All of these parts are or may be of the usual construction, and as no claims are made thereon detailed description is unnecessary.

The car shown has no end sill as such, but instead thereof the end plates 22 are provided

with flanges 44 at their lower edges, thus strengthening the same and enabling said plates to perform the usual function of an end sill in addition to their function of confining the lading. At the central portion a pressed hood 45 is secured to the end plates and serves as a support for the outer ends of the draft-beams. This end construction, however, is not new with me, and as no claims are made therefor detailed description is thought not to be necessary. The drawings also show other details of the car construction; but as none of them form any part of the present invention they are not described.

15. What I claim is—

1. In a railway-car, the combination of the body provided with plate-girder combined sides and side sills, a floor, transverse floor-supports, and vertical stiffening members secured to the car sides and provided with a portion extending outwardly from the car sides and having their lower ends bent inwardly and secured to the floor-supports.

2. In a railway-car, the combination of a center sill, body-bolsters, plate-girder combined sides and side sills supported by said body-bolsters, a floor, transverse floor-supports, and vertical stiffening members secured to the car sides and provided with a portion extending outwardly from the car sides and having their lower ends bent inwardly and secured to the floor-supports.

3. In a railway-car, the combination of the body-bolsters, plate-girder combined sides and side sills supported by said body-bolsters, a floor, transverse floor-supports formed of flanged bars, and vertical stiffening members secured to the car sides and provided with a portion extending outwardly from the car sides and having their lower ends bent inwardly and secured to the webs of the floor-supports.

4. In a railway-car, the combination of body-bolsters, plate-girder combined sides and side sills supported by said body-bolsters, cross-bearers or transoms, and vertical stiffening members secured to the car sides and provided with a portion extending outwardly from the car sides and having their lower ends bent inwardly and secured to the ends of said cross-bearers.

5. In a railway-car, the combination of a center sill, body-bolsters, plate-girder combined sides and side sills supported by said body-bolsters, transverse bearers or transoms extending across the car and connecting the center sill and car sides, and vertical stiffening members secured to the car sides and provided with a portion extending outwardly from the car sides and having their ends bent inwardly and secured to the ends of said cross-bearers.

6. In a railway-car, the combination of body-bolsters, plate-girder combined sides and side sills supported by said body-bolsters,

cross-bearers or transoms extending from side to side of the car, said cross-bearers being composed of tension and compression members and an interposed strut, and vertical stiffening members secured to the car sides and having their ends bent inwardly and secured to the ends of said cross-bearers.

7. In a railway-car, the combination of the body-bolsters, plate-girder combined sides and side sills supported by said body-bolsters, and vertical stiffening members secured to said car sides and having their lower ends bent inwardly and secured to said body-bolsters.

8. In a railway-car, the combination of body-bolsters provided with bottom flanges, of combined sides and side sills supported by said body-bolsters, and vertical stakes having their lower ends bent inwardly and secured to the lower flanges of said body-bolsters.

9. In a railway-car, the combination of the body-bolsters, a floor, transverse floor-supports therefor, vertical stakes opposite the ends of said floor-supports and having their lower ends bent inwardly and secured to said floor-supports, and other vertical stakes opposite the body-bolsters and having their lower ends bent inwardly and secured to the body-bolsters.

10. In a railway-car, the combination of the body-bolsters, of combined sides and side sills supported by said body-bolsters, a floor, transverse floor-supports, vertical stiffening members secured to the car sides and having their lower ends bent inwardly and secured to the transverse floor-supports, cross-bearers or transoms extending from side to side of the car, and vertical stiffening members secured to the car sides and having their lower ends bent inwardly and secured to said cross-bearers.

11. In a railway-car, the combination of body-bolsters, combined sides and side sills supported by said body-bolsters, a floor, transverse floor-supports, cross-bearers or diaphragms extending from side to side of the car, and vertical stiffening members opposite said bolsters, floor-supports and cross-bearers, said vertical stiffening members being secured to the car sides and having their lower ends bent inwardly and secured to the outer ends of the body-bolsters, floor-supports and cross-bearers.

12. In a railway-car, the combination of the body-bolsters, plate-girder combined sides and side sills secured thereto and having top and bottom chords, hopper-sheets extending downwardly from said car sides, a floor secured to said hopper-sheets, and vertical stiffening members secured to the car sides and extending downwardly and secured to the hopper-sheets.

13. In a railway-car, the combination of the body-bolsters, combined sides and side sills secured to said body-bolsters, a flanged bar riveted to the lower edge of said car sides, hopper-sheets riveted to the depending member

of said flanged bar, floor-plates secured to said hopper-sheets, and vertical stiffening members secured to the car sides and having their lower ends extended downwardly and bent inwardly 5 and secured to said hopper-sheets.

14. In a railway-car, the combination of the body-bolsters, combined sides and side sills supported by said body-bolsters, hopper-sheets extending downwardly from said car 10 sides, a floor, transverse floor-supports, vertical stiffening members secured to the car sides and having their lower ends bent inwardly and secured to said floor-supports, and other vertical stiffening members secured to the car 15 sides and having their lower ends extending downwardly and riveted to the hopper-sheets.

15. In a railway-car, the combination of the body-bolsters, combined sides and side sills supported by said body-bolsters, vertical stiffening members secured to the car sides and having their lower ends bent inwardly and secured to said body-bolsters, hopper-sheets extending downwardly from the car sides, floor- 20 plates secured to said hopper-sheets, and vertical stiffening members secured to the car 25

sides and having their lower ends extending downwardly and secured to the hopper-sheets.

16. In a railway-car, the combination of the body-bolsters, combined sides and side sills supported by said body-bolsters, a floor, transverse floor-supports, vertical stiffening members secured to the car sides and having their lower ends bent inwardly and secured to the floor-supports; cross-bearers or transoms extending from side to side of the car, vertical 30 stiffening members secured to the car sides and having their lower ends bent inwardly and secured to said cross-bearers; hopper-sheets extending downwardly from the car sides, floor- 35 plates secured to said hopper-sheets, and vertical stiffening members secured to the car sides and having their lower ends extending downwardly and secured to said hopper-sheets.

In testimony whereof I, the said ARNOLD STUCKI, have hereunto set my hand.

ARNOLD STUCKI.
